UNITED STATES PATENT OFFICE

145,085

DESIGN FOR A FAUCET SPRAY ATTACHMENT

Stanley Isenberg, Chicago, Ill.

Application November 15, 1945, Serial No. 123,793

Term of patent 14 years

(Cl. D91—3)

To all whom it may concern:

Be it known that I, Stanley Isenberg, a citizen of the United States, residing at Chicago, in the county of Cook, and State of Illinois, have invented a new, original, and ornamental Design for a Faucet Spray Attachment, of which the following is a specification, reference being had to the accompanying drawing, forming a part thereof.

I claim:

The ornamental design for a faucet spray attachment, substantially as shown.

STANLEY ISENBERG.
